FIG. 2

SELF-PRIMING CENTRIFUGAL PUMPS

Walter K. Jekat, West Orange, John H. Doolin, New Providence, and Theodore R. Esatow, Westfield, N.J., assignors to Worthington Corporation, Harrison, N.J., a corporation of Delaware

Filed Dec. 6, 1957, Ser. No. 701,198

11 Claims. (Cl. 103—113)

This invention relates generally to a self-priming centrifugal pump adapted to be operated at different capacities or heads by pre-selecting an impeller of a particular diameter according to the capacity or head required. More particularly, this invention contemplates providing this pump with novel means for retaining the self-priming feature regardless of the diameter size of the impeller selected.

In order to adapt this self-priming centrifugal pump for assembly line manufacturing techniques and to fulfill the requirements of the user; as for example a pump capable of delivering a variety of capacities and heads and still retaining the self-priming features, it has been found necessary to adapt the standard casing of the self-priming centrifugal pump to accommodate impellers of varying diameters. However, with this provision of varying impellers the self-priming feature of the pump has been seriously arrested.

The present invention overcomes the foregoing objection by providing the pump with a novel recirculation tube, having the novel prime retention characteristic of the apparatus disclosed in application, Ser. No. 576,442, filed in 1956, now United States Letters Patent No. 2,831,434, which is readily mounted in a pump that includes therein the pre-selected impeller providing the head and capacity required by the user.

Specifically, the invention contemplates a novel tube, readily mounted in the pump casing, that is pre-selected to coact with a particular impeller so that the operative relation between the tube and the impeller will provide the rapid self-priming characteristics for these centrifugal pumps.

It is therefore an object of this invention to provide a novel tube in a self-priming centrifugal pump which will permit the retention of the self-priming feature in pumps adapted to operate with impellers of varying diameters.

It is another object of this invention to provide means for the novel tube which maintain same in operative relation with the impeller to provide for the retention of the rapid self-priming characteristic demanded by the user.

It is a further object of this invention to adapt these self-priming centrifugal pumps for assembly line manufacturing techniques.

Further objects and advantages of the invention will become evident from the following description with reference to the accompanying drawings, in which:

Figure 1 is a side elevation of the self-priming centrifugal pump including the novel recirculation tube in section.

Figure 2 is a vertical section taken on line 2—2 of Figure 1, and

Figure 3 is a vertical section showing a modified form of the invention.

Figure 4 is a part section showing a modified form of the adjusting means.

Referring particularly to the drawings, Figure 1 shows a self-priming centrifugal pump, generally designated 10, which includes a casing 11 having a suction chamber 12,

a discharge chamber 13 and an impeller chamber or volute 14 preferably formed as integral portions of said casing. Impeller chamber 14 is adapted to receive one end of a shaft 15 which extends through a packing gland 16. An impeller 17 disposed in the impeller chamber 14 is mounted on the end of the shaft 15 by any suitable means such as threaded member 18 so that the impeller is fixed to and rotatable with the shaft 15. Rotation is imparted to the shaft 15 and impeller 17 by any suitable type of prime mover, generally designated 19, such as a gas engine which is preferably coupled to the shaft 15 at its other respective end in any well known manner and hence not more fully described herein. The usual front plate 40 is mounted in the front portion of the casing and in association with the impeller to provide a suction inlet thereto.

Upon rotation of the shaft 15, the impeller 17 flows fluid from the suction chamber 12 to the impeller chamber 14 through flow passage means 20, providing communication 20 between impeller chamber 14 and discharge chamber 13, and then to the discharge chamber 13 for use in the system in which the self-priming centrifugal pump is operatively associated.

As is the usual practice in the art, prime on start-up is 25 provided for by liquid that remains in the suction chamber 12 and discharge chamber 13 after pump shutdown. A reservoir characteristic is provided for in these chambers 12 and 13 by valve means 21 which function, as is well known in the art and hence not more fully described, to 30 provide for the retention of the initial prime for the pump.

To provide for the retention of the prime during pump operation and after the initial prime liquid has been flown to the discharge chamber, the pump casing 11 is provided with novel means, generally designated 22, which are 35 associated in operative relation with the impeller 17 whereby the self-priming characteristic is retained without regard to the diameter size of the impeller selected for operation in the pump.

Specifically, this novel means 22 comprises a recirculation chamber or guide means 23 formed in the casing 11 in spaced relation with the impeller chamber 14 and includes flow passage means 24 which provides for fluid communication between the discharge chamber 13 and the impeller chamber 14.

45 Slidably disposed in the recirculation chamber 23 is a recirculation tube 25 which includes flow passage means 26 which preferably coincide with the flow passage means 24 on the recirculation chamber 23 to provide for return flow of fluid from the discharge chamber 13 to the impeller chamber 14. Provision is made in the casing 11, 50 to be hereinafter described, for the retention of the leading and trailing edges 27 and 28, respectively, in close clearance with the impeller 17 so that the effect of the eddies in the impeller chamber acting on the fluid returning from the discharge chamber thereto is substantially arrested.

In order to limit the entry of the recirculation tube 25 into the impeller chamber and to maintain the leading and trailing edges 27 and 28, respectively, in close clearance with the impeller selected for operation in the pump 10, tube 25 is provided with stop means 29 which preferably 60 take the form of a shoulder which sits on a coacting stop means 30, preferably taking the form of a shoulder, on the recirculation chamber 23. It is not intended to limit these foregoing stop means 29 and 30 to the form shown in Figure 1 hereinabove described; it is to be understood 65 that they may take any form which effectively limits and maintains the tube 25 in close clearance with the impeller 17, as for example the form shown in Figure 3 to be hereinafter described.

70 It is evident with the provision of the compact recirculation means 22 as hereinabove described, that these self-priming centrifugal pumps are readily adapted for as-

sembly line manufacturing techniques and in addition the prime characteristic is retained with the ready insertion of a novel tube in operative position after the impeller providing the required head or capacity has been selected.

To this end the leading edge 27 can be cut back to provide smoother flow, should a small diameter impeller be selected for operation.

During operation of the pump it is imperative that the tube 25 be maintained in operative relation with the impeller 17 described hereinabove. To this end a spring member 31 or the like is disposed in the recirculation chamber 23 and held in operative relation with the port 25 by a plug element 32 associated therewith and mounted in the casing 11 as is shown in the drawings.

Accordingly, it is evident that from the foregoing description that the disclosed pump not only retains the rapid flow rate necessary for rapid self-priming but also discloses a pump that is readily adapted for assembly line manufacturing technique.

In operation and after the initial prime fluid in the reservoir 12 is flown to the discharge chamber 13, through flow passage means 20, it is returned free of air, which is separated therefrom in the discharge chamber, to the impeller chamber 14 through flow passages 24 and 26 in the recirculation means 22. This process keeps repeating itself until all the air is exhausted from the suction chamber 12.

After the air is exhausted the pump continues to pump the fluid present through the flow passage means 20 into the discharge chamber 13 where it is in turn passed through pump outlet 33 to use or other desired disposal.

Except for the modified form of stop means generally designated 35' the construction and operation of the pump shown in Figure 3 is otherwise identical to that shown in Figure 1 of the drawings and described hereinabove. Thus Figure 3 shows the stop means 35' as a stem 30' connected at one end to the base portion 29' of the recirculation tube 25' in any manner known in the art and at its other end is threadably received by a plug member 36' mounted in the casing 11. To prevent the seepage of pressurized fluid along the portion 37' of the stem threaded in the plug 36' and to prevent damage to the end extending outwardly of the casing 11' the stem is provided with a cap 38' threadably mounted thereon and in fluid sealing relation with the stem 29' at the top 39' of plug 36'.

It will be noted that with this provision of stop means 35' the tube 25' can be adjusted in close clearance with the impeller should there be a displacement of same for any reason, such as a wearing of the leading and trailing edges of the port 25'.

To adjust the tube 25' the cap 38' is removed, if in the form shown in Figure 3, and the stem 30' is manipulated to adjust the tube in close clearance with the impeller 17'.

It is evident that the flow passage means 26' in the tube 25' must be adapted to coat with flow passage means 24' in the event that the tube is adjusted after its selection for operation. To this end flow passage means 26 may be oversized as is shown in Figure 3 of the drawings.

If the cap 38' is in the form shown in Figure 4 manipulation of said cap is all that is necessary to adjust the port 25' in close clearance with the impeller, as is evident to those skilled in the art.

It will be understood that the invention is not to be limited to the specific construction or arrangement of parts shown but that they may be widely modified within the invention defined by the claims.

What is claimed is:

1. In a self-priming centrifugal pump comprising a casing, including integral therewith a suction chamber, a discharge chamber, and an impeller chamber, said impeller chamber having flow passage means interconnecting said discharge chamber and said suction chamber,

said impeller chamber being adapted to accommodate impellers of different diameters one at a time and for flowing fluid from said suction chamber through said flow passage means to said discharge chamber, guide means in said casing providing a recirculation portion therein in communication with said impeller chamber and said discharge chamber, a detachable recirculation tube slidably disposed in said guide means and having one of the ends thereof extending into said impeller chamber, fluid passage means in said tube communicating with said discharge chamber and said impeller chamber through the recirculation portion of said guide means whereby fluid flown to said discharge chamber may be returned from said discharge chamber through said recirculation tube to said impeller chamber, the end of said detachable recirculation tube extending into said impeller chamber having leading and trailing edges in close clearance with the outer periphery of the impeller mounted in said impeller chamber, stop means on said tube and coacting stop means in said guide means engaging the stop means on said tube for maintaining the leading and trailing edges on the end of said tube extending into said impeller chamber in close clearance with the outer periphery of the impeller, and means in said casing and operatively associated with said recirculation port and adapted to hold same in operating position.

2. In the self-priming centrifugal pump claimed in claim 1 wherein the stop means on said tube comprises a shoulder and the stop means in said casing comprises a cooperating shoulder for engaging the shoulder on said tube and means in said casing for urging said shoulder on said tube in abutment with the shoulder in said casing.

3. In the self-priming centrifugal pump claimed in claim 2 wherein the means for urging said shoulder on said tube in abutment with the shoulder in said casing comprises a spring mounted in said casing and in pressing relation with the end of said recirculation tube remote from the end extending into the impeller chamber.

4. In a self-priming centrifugal pump comprising a casing, including integral therewith a suction chamber, a discharge chamber, and an impeller chamber, said impeller chamber having flow passage means interconnecting said discharge chamber and said suction chamber, said impeller chamber being adapted to accommodate impellers of different diameters one at a time wherein the particular impeller may vary from a predetermined minimum diameter to a predetermined maximum diameter whereby the selected impeller flows fluid from said suction chamber to said discharge chamber, guide means in said casing providing a recirculation portion therein in communication with said impeller chamber and said discharge chamber, a detachable recirculation tube slidably disposed in said guide means and having one of the ends thereof extending into said impeller chamber, fluid passage means in said tube communicating with said discharge chamber and said impeller chamber through the recirculation portion of said guide means whereby fluid flown to said discharge chamber may be returned from said discharge chamber through said recirculation tube to said impeller chamber, the end of said detachable recirculation tube extending into said impeller chamber having leading and trailing edges in close clearance with the outer periphery of the impeller mounted in said impeller chamber, stop means on said tube and coacting stop means in said guide means for maintaining the detachable recirculation tube in fixed position in said guide means whereby the leading and trailing edges on the end of said tube extending into said impeller chamber are in close clearance with the outer periphery of the impeller.

5. In the self-priming centrifugal pump claimed in claim 4 wherein the stop means on said tube comprises a shoulder and the stop means in said casing comprises a cooperating shoulder for engaging the shoulder on said tube and means in said casing for urging said

shoulder on said port in abutment with the shoulder in said casing.

6. In the self-priming centrifugal pump claimed in claim 5 wherein the means for urging said shoulder on said tube in abutment with the shoulder in said casing comprises a spring mounted in said casing and in pressing relation with the end of said recirculation tube remote from the end extending into the impeller chamber.

7. In a self-priming centrifugal pump comprising a casing including a suction chamber, a discharge chamber and an impeller chamber as integral portions thereof, a flow passage means in the impeller chamber for communicating the suction chamber with the discharge chamber being adapted, said impeller chamber to accommodate impellers of different diameters one at a time wherein the selected impeller may vary from a predetermined minimum diameter to a predetermined maximum diameter whereby the selected impeller flows fluid from said suction chamber to said discharge chamber, guide means in said casing including a recirculation portion for communicating the impeller chamber with the discharge chamber, a detachable recirculation tube slidably disposed in said guide means and having one of the ends thereof extending into said impeller chamber, fluid passage means in said recirculation tube communicating the discharge chamber with the impeller chamber and through the recirculation portion of the guide means whereby fluid flowed to said discharge chamber may be returned from said discharge chamber through said recirculation tube to said impeller chamber, the end of said detachable recirculation tube extending into said impeller chamber having leading and trailing edges in close clearance with the outer periphery of the impeller mounted in said impeller chamber, means in the casing and operatively connected to said recirculation tube for maintaining same in operable position relative said impeller, said last mentioned means comprising a stem member disposed in the casing and connected to the base of said recirculation tube at one end and adjustable means operatively connected to the other end of said stem member for moving the leading and trailing edges of said recirculation tube relative said impeller.

8. In the self-priming centrifugal pump claimed in claim 7 wherein the means for maintaining the recirculation tube in operable position relative said impeller comprises a stem member connected to the base portion of the recirculation tube at one end and extending outwardly out of said casing at the other end, and the adjustable means being threadably connected to the portion of said stem extending out of said casing for maintaining the leading and trailing edges on the end of said tube in close clearance with the outer periphery of the impeller.

9. In a self-priming centrifugal pump comprising a casing including a suction chamber, a discharge chamber and an impeller chamber as integral portions thereof, a flow passage means in the impeller chamber for communicating the suction chamber with the discharge chamber being adapted, said impeller chamber to accommodate impellers of different diameters one at a time wherein the selected impeller may vary from a predetermined minimum diameter to a predetermined maximum diameter whereby the selected impeller flows fluid from said suction chamber to said discharge chamber, guide means in said casing including a recirculation portion for communicating the impeller chamber with the discharge chamber, a detachable recirculation tube slidably disposed in said guide means and having one of the ends thereof extending into said impeller chamber, fluid passage means in said recirculation tube communicating the discharge chamber with the impeller chamber and through the recirculation portion of the guide means whereby fluid flowed to said discharge chamber may be

returned from said discharge chamber through said recirculation tube to said impeller chamber, the end of said detachable recirculation tube extending into said impeller chamber having leading and trailing edges in close clearance with the outer periphery of the impeller mounted in said impeller chamber, and adjustable means in the casing and operatively connected to said recirculation tube for maintaining same in operable position relative said impeller.

10. In a self-priming centrifugal pump comprising a casing including a suction chamber, a discharge chamber and an impeller chamber as integral portions thereof, a flow passage means in the impeller chamber for communicating the suction chamber with the discharge chamber being adapted, said impeller chamber to accommodate impellers of different diameters one at a time wherein the selected impeller may vary from a predetermined minimum diameter to a predetermined maximum diameter whereby the selected impeller flows fluid from said suction chamber to said discharge chamber, guide means in said casing including a recirculation portion for communicating the impeller chamber with the discharge chamber, a detachable recirculation tube slidably disposed in said guide means and having one of the ends thereof extending into said impeller chamber, fluid passage means in said recirculation tube communicating the discharge chamber with the impeller chamber and through the recirculation portion of the guide means whereby fluid flowed to said discharge chamber may be returned from said discharge chamber through said recirculation tube to said impeller chamber, the fluid passage means in said recirculation tube being of larger dimension than the recirculation portion of said guide means, the end of said detachable recirculation tube extending into said impeller chamber having leading and trailing edges in close clearance with the outer periphery of the impeller mounted in said impeller chamber, means in the casing and operatively connected to said recirculation tube for maintaining same in operable position relative said impeller, said last mentioned means comprising a stem member disposed in the casing and connected to the base of said recirculation tube at one end and adjustable means operatively connected to the other end of said stem member for moving the leading and trailing edges of said recirculation tube relative said impeller.

11. In the self-priming centrifugal pump claimed in claim 10 wherein the means for maintaining the recirculation tube in operable position relative said impeller comprises a stem member connected to the base portion of the recirculation tube at one end and extending outwardly out of said casing at the other end, and the adjustable means being threadably connected to the portion of said stem extending out of said casing for maintaining the leading and trailing edges on the end of said tube in close clearance with the outer periphery of the impeller.
